FURNACE

Filed July 23, 1927

Inventor:
Henry Tielkemeyer,
By R. R. Ripley & Kingsland,
His Attorneys.

UNITED STATES PATENT OFFICE.

HENRY TIELKEMEYER, OF ST. LOUIS, MISSOURI.

FURNACE.

Application filed July 23, 1927. Serial No. 207,879.

This invention relates to furnaces, and an object of the invention is to provide a furnace of the warm air circulating type wherein in the combustion part of the furnace comprises an enclosure including a fire pot and a partition above the fire pot forming a chamber having communication to the enclosure at the side of the fire pot for conducting the products of combustion to said chamber, and thence to the outside.

Another object of the invention is to provide a furnace of the down draft type comprising an upright enclosure having a fire pot in its lower portion spaced from the wall of the enclosure, so that the products of combustion are required to pass downwardly through the grate and around the fire pot, and thence through a pipe to a compartment formed in the upper portion of the enclosure and having communication with the outside.

Other objects will appear from the following description, reference being made to the drawing which is a vertical sectional view of a furnace constructed in accordance with my invention.

The furnace comprises a shell or casing 1 having at its lower end a cold air inlet 2 and at its upper end a number of warm air outlets 3 through which the hot air passes to the several rooms.

Within the shell or casing the combustion apparatus is mounted upon an ash receptacle 4 having its upper end open and from which the ashes may be removed through a passage 5. The combustion apparatus comprises a cylindrical enclosure 6 having its wall at its lower end curving inwardly throughout its circumference to provide a portion 7 of reduced diameter set upon the upper end of the ash receptacle 4. A fire pot 8 within the enclosure 6 has a circumferential flange 9 around its upper end seated upon a support 10 rigid with the wall of the enclosure 6. The fire pot 8 is thus supported within the enclosure 6 to form an annular space 11 below the supporting flange 9. The grate 12 is supported in any appropriate manner in the lower end of the fire pot 8 slightly above the lower extremity of the reduced portion 7 of the enclosure. A fuel passage 13 opens through the shell or

casing 1 into the enclosure 6, above the fire pot 8 and is controlled by a door 14.

A horizontal partition 15 is provided in the enclosure 6 above the passage 13 and forms a chamber 16 in the upper end of the enclosure 6. An upper end wall 17 is mounted upon the upper end of the enclosure 6 and has an annular flange 18 around the outlet 19. This flange 18 supports a drum 20, the same having a flange 21 around an inlet opening 22, which flange is jointed with the flange 18. From the drum 20 the smoke, etc., is discharged through an outlet 23.

From the space 11 around the fire pot a pipe 24 opens into the chamber 16, so that the smoke, etc., passing downwardly through the grate 12 is conducted from the space 11 to the chamber 16 and to the drum 20, and thence outwardly to discharge through the outlet 23.

From the foregoing, it will be seen that I have provided an improved down draft furnace wherein most of the combustible elements and gas will be consumed, and wherein the air in the shell or casing 1 is thoroughly heated by transfer of the heat from the combustion apparatus to the air in the casing or shell. The construction and arrangement of the several parts may be varied within equivalent limits without departure from the nature and principle of the invention.

I do not restrict myself unessentially, but what I claim and desire to secure by Letters Patent is:—

1. A furnace comprising a casing, a cylindrical enclosure within the casing, a fire pot supported in said enclosure and forming an annular space around the fire pot within the enclosure, a partition in the enclosure above the fire pot, and a pipe opening from said space into said enclosure above said partition.

2. A furnace comprising a casing having a cold air inlet and warm air outlets, an ash receptacle within said casing, a cylindrical enclosure supported upon said ash receptacle, means forming a fuel inlet passage through said casing into said enclosure, a partition forming a chamber in said enclosure above said inlet passage, a fire pot supported in

said enclosure below said passage and forming an annular space within said enclosure, and a pipe opening from said space into said enclosure above said partition.

5. A furnace comprising a casing, a cylindrical enclosure supported in said casing, a partition in said enclosure, a fire pot supported in said enclosure below said partition

and having its wall spaced from said enclosure, means forming a fuel inlet into said enclosure above said fire pot and below said partition, and a pipe opening from said enclosure below the upper end of said fire pot into said enclosure above said partition. 10

HENRY TIELKEMEYER.
